INVENTOR

UNITED STATES PATENT OFFICE.

JOHN H. BRUNKEN, OF PAIGE, TEXAS.

BUGGY-SHAFT BRACE.

1,074,045.

Specification of Letters Patent. Patented Sept. 23, 1913.

Application filed January 21, 1913. Serial No. 743,386.

To all whom it may concern:

Be it known that I, JOHN H. BRUNKEN, a citizen of the United States of America, residing at Paige, in the county of Bas-
5 trop and State of Texas, have invented cer-
tain new and useful Improvements in
Buggy-Shaft Braces, of which the follow-
ing is a specification, reference being had
thereto to the accompanying drawing.

10 This invention relates to braces which are
intended to be used in connection with the
shafts of a vehicle, and the principal object
of the same is to provide a brace which will
be connected with the shaft and cross bar
15 and thus brace the shafts so that there is no
danger of the cross bar being broken or
working loose.

From an inspection of the drawings it
will be seen that this device may be either
20 formed from a strip of metal which is bent
to assume the desired shape or may be
stamped from a metallic plate.

This invention is illustrated in the accom-
panying drawings, wherein:—

25 Figure 1 is a bottom plan view of a pair
of shafts provided with the improved brace.
Fig. 2 is an enlarged perspective view show-
ing one form of the brace connected with
the shafts. Fig. 3 is a section along the line
30 3—3 in Fig. 2 to show the manner of con-
necting the brace with the cross bar. Fig.
4 is a bottom plan view of the brace. Fig.
5 is a side elevation of a pair of shafts with
the brace in place. Fig. 6 is a view of the
35 blank from which a modified form of the
invention may be formed. Fig. 7 is a view
showing the blank shown in Fig. 6 bent to
form the brace.

Referring to the accompanying drawings
40 it will be seen that this device is used to
support the cross bar 10 which connects the
shafts 11. Two of these braces are used,
one being placed at each end of the cross bar
and removably connected with the cross bar
45 and shafts so that the device may be easily
removed and placed upon a new pair of
shafts if desired.

It is noted that this device is so construct-
ed that it may be used with any type of
50 shaft since it is held in place by means of
clips which go around the shafts and cross
bar. It is also noted that in order to secure
this brace in place it is not necessary to form
holes in the shafts and, therefore, the shafts
55 and cross bar will not be weakened. When
these devices are connected with the shafts,

the cross bar will be securely held in place
and thus all danger of the cross bar break-
ing or working loose is prevented. It is also
noted that since the cross bar cannot work
60 loose the shafts will be prevented from sep-
arating.

From an inspection of Fig. 2 the form of
brace which is struck from a metallic plate
may be readily understood. In this form
65 the brace comprises a bridge 12 which is
bowed as clearly shown in Fig. 3 so that it
will form a pocket in which the cross bar
may fit. Arms 13 and 14 extend from the
bridge 12, the arm 13 extending parallel to
70 the cross bar 10 and having its outer end
portion crimped to form the pocket 15 simi-
lar to the pocket of the bridge 12. The
shaft 11 fits in this pocket 15 and is held
75 in place by means of a U-shaped clip 16
which has its reduced ends passing through
openings formed in the arm 13. Securing
nuts 17 are provided so that the shaft will
be securely clipped. The clip 18 which
80 holds the bridge 12 to the cross bar is simi-
lar in construction to the clip 16. The arm
14 extends at an angle from the cross bar
10 to the shaft 11 and has its end portion
carried parallel to the arm 13 and crimped
85 to form a pocket 19 in which the shaft 11
fits. A clip 20 similar to the clip 16 is pro-
vided so that the shaft will be securely held
in the pocket 19. It will thus be seen that
the arm 14 constitutes a diagonal brace
90 which greatly strengthens the shaft and
cross bar thus preventing any danger of the
cross bar being broken from the shaft by
any side play of the shaft.

In Fig. 7 there has been shown a modified
form of brace which is formed from the
blank shown in Fig. 6. This blank 21 is
bent along the dotted lines 22, 23 and 24,
so that it forms the bridge 25 similar to the
bridge 12, the arm 26 similar to the arm
13, and the diagonal arm 27 similar to the
100 arm 14, with its end portion 28 extending to
form a seat similar to the seat 19. Openings
29 are provided so that the securing clips
may be connected with the brace thus se-
curing the brace to the shaft and cross bar.
105 It is, of course, obvious that if desired, the
bridge 25 may be crimped in a similar man-
ner to the bridge 12 and that the outer end
of the arms 26 and 27 may be crimped to
form seats similar to the seats 15 and 19.
110 It is also obvious that, if desired, the sheet
metal form may be furnished to the person

installing the braces in the blank form shown in Fig. 6 and then bent so as to more accurately accommodate itself to the size of shaft to which it is to be applied.

Having thus described the invention, what is claimed as new, is:—

1. In combination with a pair of shafts including a cross bar, a brace having its bridge crimped to form a pocket to receive the cross bar of the shafts, an arm extending from said bridge parallel to the cross bar to one of said shafts, a second arm extending from said bridge diagonally from said cross bar to said shafts with its outer end extending parallel to the first mentioned arm, the end portions being crimped to form a pocket to receive said shaft and means for removably connecting said brace with the cross bar and shaft.

2. A brace of the character described comprising a bridge crimped to form a seat for the cross bar of a pair of shafts, arms extending from said bridge, one of said arms extending at substantially right angles to said bridge with its outer end portion crimped to form a pocket to receive the side bar of a pair of shafts, and a second arm extending diagonally from said bridge with its end portion carried parallel to said first mentioned arm and crimped to form a pocket to receive the side bar of a pair of shafts.

In testimony whereof I hereunto affix my signature in presence of two witnesses.

JOHN H. BRUNKEN.
